UNITED STATES PATENT OFFICE.

JAMES O'DONNELL, OF MANCHESTER, ENGLAND, AND PETER FRASER McLEOD, OF GLASGOW, SCOTLAND.

COMBINED FIRING VALVE, HEATER, AND BLOWBACK APPARATUS FOR OIL-FUEL-BURNING INSTALLATIONS.

Application filed January 16, 1922. Serial No. 529,671.

To all whom it may concern:

Be it known that we, JAMES O'DONNELL and PETER FRASER McLEOD, subjects of King George V of Great Britain, residing, respectively, at Manchester, England, and Glasgow, Scotland, have invented an Improved Combined Firing Valve, Heater, and Blowback Apparatus for Oil-Fuel-Burning Installations, of which the following is a specification.

This invention relates to fuel supply devices for oil fuel burning installations and has for its object to provide a novel form of combined firing valve, heater, and blow-back device for use in connection with such installations.

According to the invention two members or cages, each divided into two chambers or compartments, are secured face to face with a rotary disc or valve mounted between them and making good joints with the adjacent faces of the respective cages.

The chambers of one cage are respectively in communication with an oil supply tank and with a steam supply from a suitable generator, and the chambers of the other cage communicate respectively with an oil pipe and with a steam pipe leading to the burner or burners.

In the inner wall of the oil reception chamber adjacent to the rotary valve are two suitably disposed openings of appropriate sizes to admit of the passage of a main oil supply and of a pilot oil supply, whilst the inner wall of the oil delivery chamber, which is opposed to the oil reception chamber, has two similar openings in alignment with those previously named.

Similarly the steam reception chamber has two suitably disposed openings of appropriate sizes to admit of the passage of a main steam supply and of a pilot steam supply, and the steam delivery chamber has two similar openings in alignment with those in the reception chamber.

The centres of all the openings are disposed at an equal distance radially from the centre line of the cages, and the rotary valve or disc has a series of suitably disposed passages which by appropriate manipulation of the valve can be either moved from opposite the chamber openings to shut off the oil and steam supplies, or can open up the main oil

and main steam communications between the chambers, or in a third position can close the main oil and steam communications and open up the pilot oil and steam communications.

A suitably controlled inlet from a steam supply communicates with the oil reception chamber and when the valve disc is in appropriate position enables steam to be blown back through the oil reception chamber and the pipe leading from the oil tank for the purpose of clearing away obstructions, or through the oil delivery chamber and the oil pipe leading to the burner.

The two cages and the interposed valve disc are preferably held together by a spindle which forms a pivot for the rotary valve, suitable packings being employed between the cages and the valve to make tight joints, and means are also provided to hold the valve in the desired position.

The invention will be more fully described with reference to the accompanying drawing in which:

Fig. 1 is a front view, partly in section of a combined heater, firing valve and blow-back device constructed according to the invention, whilst

Fig. 2 is a section on the line A, A Fig. 1.

Referring to the drawing *a* represents a cage or member divided by a central rib *a'* into two chambers *a²* and *a³*, the chamber *a²* having a communication *a⁴* leading to an oil supply tank, and the chamber *a³* having a communication *a⁵* to a suitable steam supply.

A second cage or member *b* is similarly divided by a central rib *b'* into two chambers *b²* and *b³*, the chamber *b²* having an oil delivery pipe *b⁴* leading to the burner or burners and the chamber *b³* a steam delivery pipe *b⁵* also leading to the burner or burners.

The inner faces *ax* and *bx* of the cages or members *a* and *b* are flat as shewn and between them is placed a rotary valve *c*.

A spindle *d* has a circular central part *d'* which forms a pivot for the valve disc *c*, and squared portions *d²*, *d³* which pass through bosses *a⁶* and *b⁶* in the ribs *a'*, *b'* respectively. Nuts *e*, *e* on the screwed ends of the spindle enable the cages or members to be tightened up against the faces of the rotary valve disc, and packing rings *f*, *f* of suitable material

embedded in grooves, in the valve disc and in the cages or members respectively, serve to make the joints good and prevent leakage.

In the wall ax of chamber a^2 are two openings g and h of suitable size to admit of the passage respectively of a main oil supply and of a pilot oil supply, and in the wall bx of chamber b^2 are two similar openings g' and h' in alignment with the openings g and h .

In the wall ax of the chamber a^3 are two openings i and j of suitable size to admit of the passage respectively of a main steam supply and of a pilot steam supply, and in the wall bx of chamber b^3 are two similar openings i' and j' . The centres of all the openings referred to are equidistant from the centre line of the cages.

The valve or disc e has a series of openings c' , c^2 , c^3 , c^4 , corresponding respectively to the main oil, pilot oil, main steam, and pilot steam openings in the cages, and these openings in the valve are so disposed that when the valve occupies the position shewn

in Fig. 1 communication between the reception and delivery chambers is cut off; when the valve is rotated to the position indicated by the dotted line position B of the operating handle cx , the openings c^2 and c^4 are presented opposite the openings h , h' and i , i' respectively to open up the pilot oil and pilot steam communications between the reception and delivery cages and when the valve is further rotated to the position

B', the openings c' and c^3 are presented opposite the openings g , g' and j , j' respectively to open up the main oil and steam communications between the reception and delivery cages. It will be apparent that in moving to position B to open up the pilot oil and steam supply, the valve shuts off the main oil and steam supply.

Suitable means are provided to enable the valve to be held in either of the positions referred to, or in intermediate positions in which the main oil and steam supplies or the pilot oil and steam supplies will be only partially opened up. A convenient method of making such provision is to provide a fixed quadrant or segment k having a finely toothed or serrated surface k' adapted to be engaged by a suitable spring actuated member l carried by the operating handle cx of the valve. It will be obvious, however, that other equivalent means may be adopted or devised for adjustably holding the valve in desired position.

A communication m leads from a suitable steam supply into the oil reception chamber a^2 such communication being controlled by a suitable valve or cock, not shewn, when the valve is in the closed posi-

tion, opening up of this communication m enables steam to be blown back through the oil reception chamber and the oil pipe a^4 to the oil tank, to clear away any obstructions.

If the valve is moved to either the main or pilot delivery position with the communication m open, steam will be blown through chamber b^2 and will clear away obstructions in said chamber or in the oil delivery pipe leading to the burner.

The device is very compact; the oil in passing through chambers a^2 and b^2 is heated by contact with the steam chambers a^3 and b^3 ; the blow-back pipe m enables all obstructions in the oil supply chambers or delivery pipes to be cleared away; and the arrangement of the main and pilot oil and steam supplies in combination with the fine adjustment device enables the correct supplies of oil and steam to maintain the desired temperature without fluctuation to be provided.

The details of construction of the device may be varied.

Having thus described our invention, what we claim as new and desire to secure by Letters Patent is:—

1. A combined firing valve and heater, for oil fuel burning installations comprising two cages or members each divided into two chambers, the chambers of one member being connected respectively to an oil supply and a steam supply and the chambers of the other member to an oil delivery pipe and a steam delivery pipe, and a rotary disc or valve located between such cages or members and having openings adapted in certain rotary positions of the valve to be brought into alignment with openings in the walls of the cages to open up communication between the oil reception and delivery chambers and the steam reception and delivery chambers, substantially as set forth.

2. The combination with a firing valve and heater according to claim 1 of means to hold the rotary valve in adjusted position, substantially as set forth.

3. The combination with a firing valve and heater according to claim 1 of a controlled communication between the oil reception chamber and a steam supply whereby according to the position of the rotary valve steam can either be blown back through the oil supply pipe or through the oil delivery chamber and the oil delivery pipe to the burner, substantially as set forth.

In testimony whereof we affix our signatures.

JAMES O'DONNELL.
PETER FRASER McLEOD.
